(57) **CLAIM**

The ornamental design for a baseball-style sports cap, as shown and described.

DESCRIPTION

FIG. 1 is an isometric view of a cap according to the invention, showing the left side and half of the front; the right side and the other half of the front being a mirror image thereof.

FIG. 2 is a rear elevation view of the cap shown in FIG. 1. FIG. 3 is a top plan view of the cap shown in FIGS. 1 and 2; and,

FIG. 4 shows the cap of FIGS. 1 to 3, as it may be worn. The broken line showing of FIG. 4 is for the purpose of illustrating the manner in which the cap may be worn and forms no part of the claimed design.

The six broken lines that occur on the bill, the two broken lines that flank either side of the gore seams, the broken line that runs along the base of the crown (where it joins to the visor) and along the edge of the crown openings, and the two broken lines that span the segments of the crown that occur between the crown openings represent stitching, which forms part of the claimed design.
